LOCKER DOOR HANDLE

Joop M. Van Ryn, Whitby, Ontario, Canada, assignor to
The Pedlar People Limited, Oshawa, Ontario, Canada, a corporation of Canada

Filed May 28, 1968, Ser. No. 12,107

Term of patent 14 years

Int. Cl. D6—01

U.S. Cl. D33—19

The dotted lines in FIGURES 1 and 2 are for illustrative purposes only.

I claim:

The ornamental design for a locker door handle, as shown and described.
